(57) **CLAIM**

The ornamental design for a portion of an electronic mouse, as shown and described.

DESCRIPTION

FIG. 1 is a front perspective view of a portion of an electronic mouse showing my new design;

FIG. 2 is a left side view thereof;

FIG. 3 is a right side view thereof;

FIG. 4 is a front view thereof;

FIG. 5 is a rear view thereof; and,

FIG. 6 is a top view thereof.

The broken line showing of a scroll wheel region is for illustrative purposes and forms no part of the claimed design. The unshown bottom of the electronic mouse forms no part of the claimed design.
